UNITED STATES PATENT OFFICE.

PETER GENDRON, OF TOLEDO, OHIO, ASSIGNOR TO THE GENDRON IRON WHEEL COMPANY, OF SAME PLACE.

DESIGN FOR A BICYCLE HANDLE-BAR.

SPECIFICATION forming part of Design No. 25,065, dated January 21, 1896.

Application filed September 17, 1895. Serial No. 562,806. Term of patent 7 years.

To all whom it may concern:

Be it known that I, PETER GENDRON, a citizen of the United States, residing at Toledo, in the county of Lucas and State of Ohio, have invented and produced a new and original Design for Bicycle Handle-Bars, of which the following is a specification, reference being had therein to the accompanying drawings, in which—

10 Figure 1 is a perspective view of a bicycle handle-bar embodying my design. Fig. 2 is a top plan view thereof, and Fig. 3 is an end elevation thereof.

15 A is a straight horizontal cylindrical bar having at its ends the forwardly-extending sections B'. Centrally of the bar A is an enlarged ring-shaped portion B, on the lower side of which is a straight vertical cylindrical pendent portion C. From the sections B'

project forwardly the cylindrical bars E. 20 These bars are curved from the points where they meet the sections B' downwardly, forwardly, outwardly, and rearwardly, and at their ends are provided with the centrally-swelled enlargements or handles F. 25

The leading feature of my design is the shape or configuration of the handle-bar, as shown and described.

What I claim as my invention is—

The design for bicycle handle bars as herein described and shown. 30

In testimony whereof I affix my signature in presence of two witnesses.

PETER GENDRON.
